Patented Nov. 13, 1917.

UNITED STATES PATENT OFFICE.

ALBERT HOLDER, OF LOS ANGELES, CALIFORNIA.

CHANGEABLE SIGN.

1,246,600.

Specification of Letters Patent. Patented Nov. 13, 1917.

Application filed January 27, 1917. Serial No. 144,844.

To all whom it may concern:

Be it known that I, ALBERT HOLDER, a citizen of the United States, and a resident of Los Angeles, in the county of Los Angeles and State of California, have invented a new and Improved Changeable Sign, of which the following is a full, clear, and exact description.

This invention relates to signs of that type having individual letters which can be arranged in various combinations for producing a sign.

The invention has for its general objects to provide a novel form of letter unit and background on which the units are removably mounted, whereby the sign can be changed from time to time as required.

A more specific object of the invention is the provision of a changeable sign having simple, novel and effective means for locking the letter units in place.

With such objects in view, and others which will appear as the description proceeds, the invention comprises various novel features of construction and arrangement of parts which will be set forth with particularity in the following description and claims appended hereto.

In the accompanying drawing which illustrates one embodiment of the invention and wherein similar characters of reference indicate corresponding parts in both the views,

Figure 1 is a front view of a portion of a sign; and

Fig. 2 is a vertical section on the line 2—2, Fig. 1.

Referring to the drawing, 1 designates the sign letters or removable units which are independent of each other and are adapted to be mounted in a frame A. Each letter unit is made of any desired material and has extending upwardly from its top a central lug 2 which is bent backwardly and downwardly to form the bill 3 of a hook, whereby the letter units can be mounted on the frame A. The lugs 2 are in the same plane with the back face of the letter units so as to bear flat against the background or panel plate 4 of the frame A. This panel or board 4 has a horizontal groove or slot 5 which inclines downwardly from the front face 6 of the background 4, so that the hooks of the letter units can be engaged in the slot or groove to thereby support the letter units. The members 3

are of considerable extent in a horizontal direction, so that a wide bearing surface in the slot 5 will be maintained, whereby each letter will be suspended from the top and 60 will not have any chance to swing laterally.

To more effectively hold the letter units on the background, a locking strip or plate 7 is provided on the frame A at a point above the letter units, this locking strip being of such length as to engage over the front of the lugs 2 of a plurality of letter units, and it is connected at its upper edge to the cap-piece 8 of the sign body A by 65 hinges 9. The holding or locking strip 7 thus hangs by gravity with its lower marginal portion engaged with the lugs 2, so that it is impossible for the letter units to become detached from the sign body without the locking strip 7 being first swung upwardly and the letter units lifted upwardly and forwardly, as shown by the dotted lines in Fig. 2. While the letter units are assembled, the locking member 7 is held 70 raised so as to be out of the way and to uncover the slot 5. When the locking plate is in normal position, as shown in Figs. 1 and 2, it covers the slot 5 and also the lugs 2, so that the sign has the appearance of fixed 75 letter units permanently fastened to the background of the sign, since the particular fastening means will be concealed. If desired, the locking strip 7 can be clamped by suitable means, such as a screw 10 swiveled in the strip 7 and having a threaded 80 engagement with a socket 11 in the background.

From the foregoing description taken in connection with the accompanying drawing, the advantages of the construction and 85 method of operation will be readily understood by those skilled in the art to which the invention appertains, and while I have described the principle of operation, together with the device which I now consider to be the best embodiment thereof, I 90 desire to have it understood that the device shown is merely illustrative and that such changes may be made when desired as fall 95 within the scope of the appended claims.

Having thus described my invention, I claim as new and desire to secure by Letters Patent:

1. The combination of a sign background having a longitudinal slot, sign character 100 units each having a hook at its top to engage in the slot, and a locking element 105 ex-

tending longitudinally of the sign at a point over the character units and engaging and covering the hooks and covering the slot for locking the character units on the background.

2. The combination of a sign background having a horizontal slot inclined downwardly from the front face, a plurality of sign character units bearing on the background at a point under the slot, upwardly

- 10 extending lugs on the units and having downwardly and rearwardly bent extremities engaged in the slot for supporting the units, and a strip hinged at its top edge on the background and having its lower marginal portion extending over and contacting with the lugs and covering the said slot to retain the units in place.
- 15

3. The combination of a sign background having a horizontal slot inclined downwardly from the front face, a plurality of sign character units bearing on the background at a point under the slot, upwardly 20 extending lugs on the units and having downwardly and rearwardly bent extremities 25 engaged in the slot for supporting the units, a strip hinged at its top edge on the background and having its lower marginal portion extending over and contacting with the lugs and covering the said slot 30 to retain the units in place, and means for clamping the said element with respect to the background to hold the element against movement.

ALBERT HOLDER.
